INVENTOR

GEORGE J. BURKHARDT

BY Geo. H. Strong,

HIS ATTORNEY.

UNITED STATES PATENT OFFICE.

GEORGE J. BURKHARDT, OF BURLINGAME, CALIFORNIA.

TOILET.

971,826.

Specification of Letters Patent.

Patented Oct. 4, 1910.

Original application filed May 8, 1908, Serial No. 431,651. Divided and this application filed August 2, 1909.
Serial No. 510,920.

To all whom it may concern:

Be it known that I, GEORGE J. BURKHARDT, citizen of the United States, residing at Burlingame, in the county of San Mateo and State of California, have invented new and useful Improvements in Toilets, of which the following is a specification.

My invention relates to toilets. Its object is to provide a disappearing toilet which can be placed in any room and moved into and out of a cabinet, being only exposed when desired for use; which will have no flush tanks, floats or ordinary valve arrangements, and which will be simple in construction, sanitary, and not likely to get out of order.

The invention consists of the parts and the construction and combination of parts as hereinafter more fully described and claimed, having reference to the accompanying drawings, in which—

Figure 1 is a side elevation in partial section of the invention. Fig. 2 is a plan view of the same. Fig. 3 is a detail of a valve mechanism for the flushing arrangement.

1. A represents a bowl of suitable construction having a suitably packed ball-bearing sleeve joint 2 suitably mounted to turn on the waste pipe 3 so that the bowl may be swung from side to side and moved into or out of a suitable cabinet 4, which latter may be built into the wall of the building or room.

5 is a water supply pipe connecting with the main, or any other suitable source of supply, and through which the water is admitted into the bowl for flushing purposes. As here shown, the pipe 5 enters a vertically arranged cylinder 6 which has a horizontal cylindrical extension 7, in which extension a

40 suitably packed piston 8 is adapted to operate. A valve 9 seats in the upper end of the cylinder 6, and the stem 10 of this valve carries a roller 11 adapted to ride on the rod 12 of piston 8. This piston-rod 12 has a cam or wedge 13 suitably positioned to engage the roller 11 so that when the rod 12 is pulled in one direction it will lift valve 9 and allow the water to flow from the pipe 5 into the valve casing 6; the valve 9 being closed automatically in a manner shortly to be described.

The stem 10 of valve 9 passes on down through the hollow stem 14 of a lower regulating valve 15, which is movable toward and from its seat 16 at the lower end of the

55 valve casing 6; the lower end of the valve

casing opening into a short pipe 17 disposed in axial line with the pivoted sleeve 2 of the bowl. This pipe 17 forms a pivot for the flushing pipe 18 which connects with the top of the bowl, so that when valves 9 and 15 are open, and the bowl swung out into the room into operative position, the water can pass directly down through the valve casing 6 and through pipes 17 and 18 into the bowl, and thence into the waste-pipe. 60 The valve 15 is mounted loose on the stem 10 so as to be movable independent of valve 9. The function of the valve 15 is that of a regulator to govern the flow of the water into the bowl, and its adjustment is effected 70 by suitable means, as the ratchet 19 operated by a conveniently arranged thumb-screw 20. The rear end of the casing extension 7 is closed, and the piston 8 has a small port 21 connecting the space on the opposite sides 75 of the piston, through which the fluid may slowly circulate. A spring 22 tends normally to press the piston 8 outward from the valve stem 10 so as to allow the valve 9 to close. A suitable vent-pipe 23 is connected 80 with the top of the waste-pipe 3 and leads outside the building, so as to remove any noxious gases that might be generated.

Any appropriate means may be employed to effect the oscillation of the toilet into 85 and out of the casing. As here shown, the sleeve 2 carries a fixed mutilated gear 24, engaged by a corresponding segmental rack 25, which latter is carried on a lever 26 fulcrumed at 26'. The lever 26 is connected 90 by a link 27 to the bell crank 27'. A hand-operating lever 28 is connected with a bell crank 27' by a link 28', thus it will be seen that by rocking the lever 28 in one direction, the parts will be operated to move the device 95 into the casing, and when the lever is moved in the opposite direction the bowl will be swung outward into operative position so as to open up communication between the stack pipe and the bowl through the port 29. 100

It is understood that the bowl and the stack pipe are only in communication through the passageway 29 when the bowl is swung outward into operative position. Whenever it is swung inward into the cabinet, this opening 29 is closed, valve-fashion, by the turning sleeve 2 so that the gases from the stack-pipe cannot pass into the room. 105

In operation, the door of the cabinet is 110

opened and the bowl swung outward into the position shown in Fig. 1, or in dotted line position, Fig. 2. Assuming that the thumb-screw 20 and ratchet 19 have been 5 turned and set permanently so as to give the desired outlet around valve 15, the operator simply pulls outward on the handle 30 which is attached to the piston-rod 12. This causes the cam 13 to lift up on roller 11, opening valve 9. The water can then pass in 10 from pipe 5 around valve 9, through the casing, and out around valve 15 and through the pipes 17-18 into the bowl; thence to the sewer. Releasing the hold on the handle 30 15 allows the spring 22 to act, and the period of flushing will depend on the time that it takes this spring to push the piston 8 backward against the slow flow of the fluid through port 21 from the space behind piston 8; it being understood that the combined 20 pressure exerted on piston 8 by the water pressure in the casing and the spring 22, is in excess of the pressure at the outlet into pipe 17. As soon as the cam 13 rides out 25 from underneath the roller 11, the valve 9 is seated by the pressure in pipe 5, and the flushing operation ceases.

This application is a division of original application upon which there has been issued 30 to me Patent No. 993,619 dated September 7, 1909.

Having thus described my invention, what I claim and desire to secure by Letters-Patent, is:

35 1. In a toilet, the combination of a stack-pipe, a bowl having a collar-bearing turnable in suitable bearings on said stack-pipe, means by which the stack-pipe and bowl are in communication when the bowl stands in one position and out of communication when the bowl stands in another position, and means for admitting water to the bowl for flushing purposes, said last means comprising a cylinder having a horizontal extension 40 and an inlet and outlet valve at opposite points one on each side of said extension, a piston operating in the extension and adapted to actuate said valves during its movement, and means for operating the piston.

45 2. In a toilet, the combination of a stack-pipe, a bowl having a collar-bearing turnable in suitable bearings on said stack-pipe, means by which the stack-pipe and bowl are in

communication when the bowl stands in one 55 position, and out of communication when the bowl stands in another position, a flushing pipe entering the bowl and turning on a hollow pivot co-axial with the pivot of said sleeve, and means for admitting water 60 through the hollow pivot of said flushing pipe, said last named means comprising a cylinder having a horizontal extension intermediate of its ends, and having an inlet at one side of said extension and an outlet at 65 the other side, valves controlling said inlet and outlet and a piston operating in said extension cross-wise of the valves and having means for operating the valve during its movement.

70 3. In a toilet, the combination of a stack-pipe, a bowl having a collar-bearing turnable in suitable bearings on said stack-pipe, means by which the stack-pipe and bowl are in communication when the bowl stands in one 75 position, and out of communication when the bowl stands in another position, means including a mutilated gear connected with the bowl and a mechanism for operating the same to induce rotary motion to the bowl 80 a flushing pipe entering the bowl and turning on a hollow pivot co-axial with the pivot of said sleeve, means for admitting water through the hollow pivot of said flushing pipe, and a vent-pipe connected with the 85 stack-pipe back of the bowl and adjacent to said sleeve.

4. In a toilet, the combination of a stack-pipe, a bowl having a collar-bearing turnable in suitable bearings on said stack-pipe, 90 means by which the stack-pipe and bowl are in communication when the bowl stands in one position, and out of communication when the bowl stands in another position, means for admitting water to the bowl for flushing 95 purposes, and means for turning the bowl, including a gear member movable with the bowl, a pivotally mounted segmental rack engaging said gear member, and means for oscillating the rack.

100 In testimony whereof I have hereunto set my hand in the presence of two subscribing witnesses.

GEORGE J. BURKHARDT.
